UNITED STATES PATENT OFFICE.

EDWIN D. KING, JR., OF VALDOSTA, GEORGIA.

STERILIZER.

Application filed December 4, 1926. Serial No. 152,660.

This invention relates to a sterilizer and has for its object to provide, in a manner as hereinafter set forth, an apparatus of such class for sterilizing public drinking vessels 5 to remove therefrom disease producing bacteria, thereby rendering safe, which otherwise might be a dangerous drinking vessel, such as when it has been previously used by persons suffering from trench mouth, tuberculosis, or other dangerous communicable 10 diseases.

A further object of the invention is to provide, in a manner as hereinafter set forth, a sterilizing apparatus for subjecting public 15 drinking vessels to steam heat, under pressure, and arranged to maintain the pressure to produce a high temperature which is very effective in the destruction of disease-producing bacteria.

Further objects of the invention are to provide, in a manner as hereinafter set forth, a sterilizing apparatus which is simple in its construction and arrangement, strong, durable, compact, thoroughly efficient in its 20 use, conveniently operated, readily set up, and comparatively inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications 30 can be resorted to which fall within the scope of the claim hereunto appended.

In the drawings wherein like reference characters denote corresponding parts 40 throughout the several views:

Figure 1 is a sectional elevation, of a sterilizing apparatus in accordance with this invention, and further illustrating a tray of drinking vessels arranged therein.

Figure 2 is a top plan view of the hinged cover.

Figure 3 is a top plan view of the tray or container for the drinking vessels or glasses to be sterilized.

Figure 4 is an elevation illustrating a tray removing means and showing the adaptation of the tray in connection with said means.

A sterilizing apparatus, in accordance with this invention, comprises a body portion referred to generally by the reference character 1 which is of cylindrical contour or in

other words formed of a cylindrical body portion 2 of substantial height, and provided at its upper end with a laterally extending annular flange 3. The body portion 2 is open at its top and closed at its lower end, by a bottom 4, which is arcuate in contour in cross section or in other words the bottom 4 is convexed.

The flange 3 is formed with notches 5 disposed radially with respect to the axis of the body portion 2. The notches 5 are arranged in spaced relation. The body portion 2 has projecting from its outer face, a series of spaced pairs of apertured lugs 6. The lugs 70 of each pair are spaced from each other. The upper ends of the lugs are integral with the lower face of the flange 3. The inner faces of the lugs of each pair are flush with the side edges of the notch.

The open top of the body portion 2, is closed by a concaved hinged lid referred to generally by the reference character 7, and comprises a body portion 8 which in cross section, is of dome-shaped contour and 80 formed integral with the body portion 8, is a laterally extending flange 9 of the same width as the flange 3, and which is arranged in superposed relation with respect to the flange 3 when the lid 7 is in closure position. 85 The flange 9 is provided with spaced notches 10 which align with the notches 5 in the flange 3. A packing element 11 is interposed between the flanges 3 and 9 and said element is also notched to register with the 90 notches in said flanges.

Positioned between each pair of lugs 6, as well as being pivotally connected therewith as at 12, is a swinging bolt 13 having its lower portion formed with an opening 14 for the reception of the pivot 12. The bolt 13 is adapted to be swung into a set of registering notches and to extend above the flange 9. Mounted on each bolt 13 is a threaded clamping member 14 of the wing type, and 95 which threadably engages with the threaded upper end 15 of the bolt 13. The members 14 are adjusted downwardly on the bolts 13, and clamp against the upper face of the flange 9 to provide a steam tight joint between the lid 7 and top of the body portion 1.

Carried by the lid 7, as well as communicating with the sterilizing chamber 16, formed by the body portion 2 and lid 7, is a pressure gauge 17. The lid 7 has further secured thereto a safety valve 19 which also 110 communicates with the chamber 16.

The body portion 2 in proximity to the flange 3, is formed with a nipple 20 which communicates with the chamber 16 and said body portion 2, in proximity to its lower end is also provided with a nipple 21 which communicates with the chamber 16 in close proximity to the upper face of the bottom 4. A steam feed pipe is indicated at 22, and which communicates with a suitable source 10 of steam supply. The pipe 22 is provided with a T-coupling 23 and connected to the latter is a vertically disposed steam supply pipe 24, which opens into the nipple 20 and is provided intermediate its ends with a cut-15 off valve 25. Extending downwardly from the coupling 23 is a vertically disposed steam supply pipe 26, which opens into a T-coupling 21' carried by the nipple 21. The pipe 26 is provided intermediate its ends with a 20 cut-off valve 27. By the arrangement of steam supply pipes shown, the steam can be supplied simultaneously to the chamber 16 at the upper and lower ends thereof, or it can be independently supplied to the upper 25 or to the lower end thereof. Attached to the T-coupling 21' is a normal closed valve 18, which permits of reducing the pressure within the body portion 2 and also provides for the discharge, at the bottom of the body 30 portion 2, of water and dead steam, as they are undesirable for the best sterilization.

Secured to the inner face of the body portion 2, in close proximity to the lower end thereof, is a series of spaced supporting 35 brackets 28, in the form of angle irons and which act as means for supporting a tray, container, holder or crate referred to generally by the reference character 29, for the drinking vessels or glasses 30 which are to be 40 sterilized.

The tray, container, holder or crate will be hereinafter termed a tray and preferably the height thereof is slightly greater than the drinking vessels to be sterilized. The 45 tray 29 conforms in contour to the shape of the body portion 2, but it is slightly less than the interior dimensions of the body portion 2, whereby when the tray 29 is mounted in position it will be spaced from the wall of the chamber 16. Preferably the body portion 2 is of a height to receive six 50 trays, arranged in superposed relation, and with the lower trays supporting the upper trays and with the lowermost tray mounted 55 on the brackets 28.

As shown the tray consists of an annular body portion 31, formed throughout with a single row of circumferentially extending spaced circular openings 32. The openings 60 are spaced equi-distant with respect to each other and preferably each opening is an inch and a quarter in diameter and further of a diameter greater than half the height of the body portion 31. The openings are spaced 65 equi-distant from the upper and lower ends

of the body portion 31. The tray further includes a bottom 33 which is integral with the lower end of the body portion 31, and which is formed throughout with spaced openings 34 of the same diameter as the diameter of 70 the openings 32.

The flange 9 of the lid 7, is hinged to the flange 3 of the body portion 2, as at 34'.

The drinking vessels after being washed, are placed in the chamber 16, the lid is then 75 closed and the steam turned in and allowed to increase pressure to the lethal point for bacteria for the required length of time, five to ten pounds for twenty to thirty minutes. The pressure is then released 80 through the medium of the valve 18, and when the apparatus and contents have cooled sufficiently the traps are removed. The action of the steam upon the drinking vessels will entirely destroy the pathogenic 85 bacteria. The drinking vessels are mounted in the trays bottom up. As the trays are perforated throughout, the steam can circulate through the superposed trays and attack the drinking vessels mounted therein. 90

As the steam is supplied under pressure it has an unusually effective result and dry steam under ten to fifteen pounds of pressure will render disease germs harmless if continued from twenty to thirty minutes. 95

For conveniently removing and replacing a tray of drinking vessels, a lifting device as illustrated in Figure 4, is shown connected with a tray. The lifting device consists of a resilient yoke-shaped member 35 of inverted contour and which has its top bent in an overlapping manner to provide a spring loop 36. The arms of the member 36 are indicated at 37, 38 and each has its lower end formed with a hook 39. Connected to the spring loop 36 is an elongated bar 40 provided with a hook 41 at its lower end. The lifting device is in the form of a tripod, and when connected with the tray 100 its inherent resilient characteristic will maintain it in clamping position with respect to the tray. 105

It is thought that, the many advantages of a sterilizing apparatus, in accordance with this invention, can be readily understood, and although the preferred embodiment of the invention is as illustrated and described, yet it is to be understood that changes in the details of construction can be had which will fall within the scope of 110 the invention as claimed. 115

What I claim is:

A sterilizing apparatus comprising an open top body portion having a closed convex bottom, supports within said body portion in close proximity to said bottom, a concave lid for said body portion and forming in connection with the latter a sterilizing chamber, means for hinging the lid to the body portion, means coacting with the body 125 130

portion and lid to form a steam tight joint therebetween, removable means mounted on said supports and adapted to contain the articles to be sterilized, a nipple extended laterally from the body portion below said supporting means and in close proximity to the lower end of said bottom, a vertically disposed steam supply pipe opening into said chamber near its upper end and further opening into said nipple, a cut-off car-

ried by said pipe in proximity to its upper end, a cut-off carried by said pipe in proximity to its lower end, a feed pipe opening into said supply pipe between said cut-offs, and a normally closed outlet valve communicating with said nipple. 15

In testimony whereof, I affix my signature hereto.

EDWIN D. KING, JR.
